UNITED STATES PATENT OFFICE.

WILLIAM WEIR HENRY, OF WOLLASTON, MASSACHUSETTS, ASSIGNOR TO S. H. COUCH CO., INC., OF ATLANTIC, MASSACHUSETTS.

ANNUNCIATOR-DROP.

1,107,610.

Specification of Letters Patent. Patented Aug. 18, 1914.

Application filed October 24, 1912. Serial No. 727,511.

To all whom it may concern:

Be it known that I, WILLIAM WEIR HENRY, a citizen of the United States, and residing at Wollaston, in the county of Norfolk and State of Massachusetts, have invented certain new and useful Improvements in Annunciator-Drops, of which the following is a specification.

This invention relates to devices of the 10 annunciator drop type wherein an indicator of light weight is to be rapidly alternated, to and fro; and has special reference to the means for preventing the tendency to rebound on the part of the indicator due to 15 the quick impact of the blow.

In the illustrations which accompany and form part of this specification, Figure 1 is a front view of an annunciator drop, embodying my invention. Fig. 2 is a central section 20 of Fig. 1, substantially in the direction indicated by the numerals 2—2 of Fig. 1, the lower of said numerals having a directing line. The indicator is shown in mid-position. Figs. 3 and 4 are end views showing the 25 shield in opposite positions. Figs. 5 and 6 are modifications.

The indicator or disk 1 is pivotally mounted at 2 in connection with the supporting frame 3, said pivot 2 also supporting the armature 4 which, in connection with the magnets 5 and 6 are also mounted on frame 3 and form a well-known means for 30 alternating indicator 1. This indicator is provided with a slot 7, here shown concentric with pivot 2, and through this slot projects a lug 8, formed on the armature 4 and adapted to alternately engage the ends of slot 7 for the purpose of imparting motion to the indicator. Lug 8 is not designed to 35 limit the throw of indicator 1 and is preferably formed so that armature 4 has gained a slight momentum before the impulse is given to the indicator, this momentum being 40 slightly greater at the "call" than at the 45 "re-set." A wiring circuit 9 is indicated in diagram in Fig. 1.

The foregoing applies to the general construction of annunciator drop mechanism and does not, in itself, comprise new matter 50 under this application.

As indicator 1 is of light construction and as its movements are rapid, it is necessary to provide means for preventing any tendency toward rebound; so I have invented 55 and shown in the drawings a stop 10 so po-

sitioned as to receive the impact of the blow delivered by the indicator and so shaped as to cause that impact to be delivered as a glancing blow. By the term "glancing blow" is meant one that is not abruptly 60 checked at its first point of impact.

Referring to Figs. 3 and 4, it will be noticed that the stop 10 is formed with a receiving surface somewhat inclined to the plane of motion in which indicator 1 acts, so 65 that when the latter comes in contact with the former, it is permitted a slight further advance, but in a changed direction. This further advance serves to introduce sufficient friction between the parts that are in connection with the moving indicator to overcome 70 the rebound tendency, and this forms the main feature of my invention. As the "call" blow is preferably sharper than that of "re-setting" the tendency to rebound is greater 75 in the former. This difference of impact could be increased until the rebound on the "reset" could not overcome the force of gravity, and hence but one of my stops is essential, viz.—that for the "calling" blow; 80 but in practice this difference is slight and I prefer to provide similar stops on each side. Those well-skilled in the art will understand that it is essential that the "call" should be positive and reliable, and this is best obtained by a sharp, quick blow. The 85 positiveness of action in the re-setting or return of indicator 1 to non-signaling position is less imperative, though equally desirable.

Fig. 5 shows the wedge 10' reversed, but 89 the action is the same as in the other figures.

In Figs. 3, 4 and 5, three different results of the wedging impact are portrayed in exaggerated form in order that the operation of my invention may be more readily seen; 95 but it will be understood that all three actions may, in practice, be united in effect. In Fig. 3 the wedge stop 10 has caused a slight climbing of the indicator 1 vertically on its pivot 2 to bring an increase of friction 100 against the pivot-head. In Fig. 4 there is shown a slight warping of the indicator against the stop, thereby introducing another element of friction which was lacking before the impact. In Fig. 5 it will be noticed that 105 indicator 1 is shown as being slightly tipped on the pivot 2 thereby increasing the friction on the shank of said pivot. The effect of this increase of friction is most effective at the moment when the rebound tendency is 110

greatest and, as found in practice, it will entirely overcome such tendency. In Fig. 6 this wedging effort is applied to the periphery of indicator 1 by the stops 10'', 5 causing an increase of friction there and on the pivot 2. Of course it is understood that the warping and wedging effect on the indicator is but momentary, as it finds its thrown position of rest at the initial point 10 of impact.

Attention is called to the unit construction of my device whereby a series of drops may be assembled on a common base through the agency of slotted holes 3', by reason of which, 15 any unit may be replaced by simply loosening the screws which may fasten frame 3 on said base and slipping said frame out of its position. So far as I know I am the first to make each unit complete in itself.

20 I do not limit myself to the precise construction illustrated.

What I claim is:—

1. An annunciator drop comprising a frame, an electromagnet mounted on said 25 frame, and an indicator movably mounted in connection with said frame and adapted to be thrown from a position of rest by said magnet; in combination with a rigid stop adapted to receive the impact of the moving 30 indicator, said stop being so shaped as to permit a slight continued advance of said indicator beyond its initial point of impact, and so positioned as to automatically compel the indicator to return to said initial point 35 of impact as its final thrown position.

2. An annunciator drop comprising a frame, an electromagnet mounted on said frame, and an indicator movably mounted in connection with said frame and adapted to be thrown from a position of rest by said 40 magnet; in combination with a stop adapted to receive the impact of said indicator as a glancing blow, and so positioned as to automatically compel said indicator to ultimately come to rest at its position of initial 45 impact.

3. An indicator adapted to be thrown from a position of rest, means for causing such throw, and a stop adapted to receive the impact of said indicator as a glancing 50 blow, said stop being so positioned as to ultimately bring said indicator to rest at the position of initial impact.

4. An indicator adapted to be thrown from a position of rest, means for causing 55 such throw, and a rigid stop adapted to receive the impact of the moving indicator, said stop being so shaped as to permit a slight advance of said indicator beyond its first point of impact, and so positioned as 60 to compel said indicator to automatically return to said first point of impact as its final thrown position.

In testimony whereof I have affixed my signature, in presence of two witnesses.

WILLIAM WEIR HENRY.
